(57) **CLAIM**

The ornamental design for a bird deterrent spike, as shown and described.

DESCRIPTION

FIG. 1 is a front, left and top perspective view of a bird deterrent spike showing my new design;
FIG. 2 is a rear, right and bottom perspective view thereof;
FIG. 3 is a front view thereof;
FIG. 4 is a rear view thereof;
FIG. 5 is a left side view thereof;
FIG. 6 is a right side view thereof;
FIG. 7 is an enlarged top plan view thereof;
FIG. 8 is an enlarged bottom plan view thereof;
FIG. 9 is an enlarged view of area 9 in FIG. 1; and,
FIG. 10 is an enlarged view of area 10 in FIG. 2.
The broken lines in the figures illustrate portions of the bird deterrent spike that form no part of the claimed design. The dot-dash broken lines represent boundaries of the enlarged portions and form no part of the claimed design.

1 Claim, 10 Drawing Sheets
